No. 754,715.

PATENTED MAR. 15, 1904.

T. A. SHEA.

SEMIELLIPTIC SPRING.

APPLICATION FILED JULY 8, 1903.

NO. MODEL.

UNITED STATES PATENT OFFICE.

THOMAS A. SHEA, OF OSWEGO, NEW YORK, ASSIGNOR TO GEORGE B. SLOAN, JR., OF OSWEGO, NEW YORK.

SEMIELLIPTIC SPRING.

SPECIFICATION forming part of Letters Patent No. 754,715, dated March 15, 1904.

Application filed July 8, 1903. Serial No. 164,694. (No model.)

To all whom it may concern:

Be it known that I, THOMAS A. SHEA, a citizen of the United States, residing at Oswego, in the county of Oswego and State of New York, have invented certain new and useful Improvements in Semielliptic Springs; and I do hereby declare the following to be a full, clear, and exact description of the invention, such as will enable others skilled in the art to which it appertains to make and use the same.

My invention relates to end plates for semi-elliptic springs, to which the stirrup carrying the load is fitted; and it consists in such a construction of the end plate that it may be set or adjusted in position on the end of the main leaf of a spring of ordinary construction and there locked securely by the assembling of the other parts of the spring without the use of the tool to bend or weld the parts into engagement and with no inconvenient modification in the form of the spring.

My invention consists in forming the end plate with an extension on its outer end and extending downwardly and inwardly to engage both with the end of the main leaf and with its under surface, so that the end plate is locked securely in position by the engagement therewith of the second leaf.

My invention will be understood by reference to the drawings herewith, in which the reference-letters of the specification indicate the corresponding parts in all the views.

Figures I to VII illustrate my invention applied to a so-called "gib" end plate, Figs. VIII to XI to a stirrup end plate. Fig. I shows my end plate in position on a spring, at one end shown in elevation, at the other in section. Figs. II, III, IV, and V are respectively side elevation, corresponding section, end elevation, and top plan of an end plate enlarged. Figs. VI and VII show the ends, respectively, of the first and second leaves of a spring for a gib end plate and hanger. Fig. VIII is a longitudinal section of a stirrup end plate on its spring. Figs. IX and X are respectively side elevation and bottom plan of a stirrup end plate enlarged. Fig. XI is the end of a suitable form of second leaf for a stirrup end plate.

In the figures, 1 indicates the main leaf, and 2 the end plate or bearing-plate supported thereon and having at its outer end the extension, preferably in the form of an integral downwardly-depending shoulder 3, equal in depth to the thickness to the main leaf, with whose end it engages, and of an integral lug 4 on the lower edge of the shoulder and extending under the main leaf, with which it engages, to retain the end plate in position. The second leaf 7 is preferably elongated to be flush with the outer edge of the end plate, and its usual slot 8 is elongated to receive the lug. The end plate is grooved at 11 for pin 12 of hanger 13, depending through usual slots 14 and 15 in the end plate and main leaf, respectively. 18 is the usual strap or band. In the other views the end plate is adapted to receive the so-called "stirrup-hanger" 20, depending on each side. The end plate and main leaf are unslotted, and the second leaf is provided with a slot 21, merely of sufficient size or length to receive the lug, whose outer end is preferably rounded snugly to fit the end of the slot, though these parts may be of any suitable form, and the lug might under some circumstances be made thinner and the leaf-slot merely in the form of a depression on the upper surface to receive it.

I prefer to make my end plates with side flanges 23 to engage with the edges of the main leaf and to assist in maintaining the end plates securely in position against lateral strains. As the sides of the end plate should be flush with the edges of the spring, these flanges are curved on their inner surfaces and are merely of sufficient depth to fit the upper portion of the rounded edges of the main leaf.

I do not limit myself to the exact form here shown, as that may be varied without departing from the spirit of my invention.

My end plate, economically made of wrought or malleable iron or other suitable material, requires no adjustment or tool to secure it in place, for it is merely set by hand on the end of the main leaf and there securely locked in place by the engagement of the second leaf when the parts are assembled and secured by the band, so that it cannot be removed with-

out removing the securing band, strap, or bolt. When this is done, the end plate is released and may be removed, to be restored to position uninjured when the parts are reassembled. One of its great advantages is that it may be used with springs which are not specially constructed to receive it, any such modification of springs being inconvenient for the railroad company or other user commonly not provided with special tools. Bending a leaf of the spring or cutting recesses in it or otherwise mutilating a leaf, particularly the ends of the main leaf, adds to the expense, complicates the manufacture, and is most objectionable, because it weakens the spring itself. The only change required in the spring is easily effected in any shop, consisting merely in elongating the slot in the second leaf or in punching a short slot therein to receive the lug, requiring only the ordinary tool. The second leaf is also slightly longer than the first or main leaf.

Having thus described my invention, what I claim, and desire to secure by Letters Patent, is—

1. As a new article of manufacture, an end plate fitted to a leaf-spring, and having an end projection to engage with end and under surface of the main leaf and to be engaged by the second leaf.

2. As a new article of manufacture, an end plate fitted to a leaf-spring, and having an integral end extension extending first downwardly to engage with the end of the main leaf and then inwardly to engage with the under surface of the main leaf, and adapted to be engaged also by the second leaf.

3. As a new article of manufacture, an end plate for semielliptic springs, substantially equal in width to the spring and provided with a shoulder or flange extending across its end, equal in depth and length to the end of the main leaf, and with an inwardly-extending lug centrally arranged on the under surface of the shoulder, adapted to engage with the under surface of the main leaf and with an opening in the second leaf.

4. In a semielliptic spring, the combination with the main leaf of usual form and the second leaf perforated near its end, of an end plate or bearing-plate fitted to rest on the main leaf, an integral shoulder on the plate fitted to the end of the main leaf, and an integral locking-lug on the shoulder to engage with the under surface of the main leaf and with a perforation in the second leaf.

5. In a semielliptic spring, the combination with the main leaf of usual form and a second leaf perforated near its end and extending outwardly beyond the main leaf, of an end plate fitted to rest on the outer end of the plate, substantially equal in depth to the thickness of the main leaf, and an integral lug on the lower surface of the shoulder, inwardly extending therefrom to engage with the un-

der surface of the main leaf and to fit the outer end of the perforation in the second leaf.

6. In a semielliptic spring, the combination with the main leaf of usual form and with the second leaf slotted near its end and extending outwardly beyond the main leaf, of an end plate or bearing-plate fitted to the upper surface of the main leaf at its end, an integral flange or shoulder extending across the end of the plate and downwardly depending therefrom, substantially equal in depth to the thickness of the main leaf and adapted to engage with its end, an integral lug on the lower surface of the flange inwardly extending to engage with the under surface of the main leaf and adapted to engage with the outer end of a slot in the second leaf.

7. In a semielliptic spring, the combination with the main leaf of usual form, of an end plate fitted to rest on the main leaf at its end, an integral flange or shoulder extending across the outer end of the end plate and being substantially equal in depth to the thickness of said leaf, an inwardly-extending lug on the lower surface of the flange having a curved front end and adapted to engage with the under surface of the main leaf, and the second leaf having its end extending outwardly to lie substantially flush with the outer end of the end-plate shoulder and provided with a slot fitting said lug.

8. In a semielliptic spring, the combination with the main leaf of usual form, of an end plate or bearing-plate fitted to rest on the end of the main leaf, integral side flanges on the plate curved on their inner surfaces to engage with the upper portion of the main leaf and having their outer surfaces arranged substantially flush with the widest portion of the main leaf, an integral flange or shoulder extending across the end of the end plate and downwardly extending to an extent substantially equal to the thickness of the end main leaf to engage therewith, an integral lug having a curved outer end on the lower surface of said flange or shoulder and inwardly extending therefrom to engage with the under surface of the main leaf, and the second leaf having its end arranged to extend outwardly beyond the main-leaf end and to lie flush with the end of the end plate, and provided with a slot near its end formed to receive said lug and fitted to the curved outer end, substantially as described and shown.

9. As a new article of manufacture, an end plate for a leaf-spring, substantially equal in width to the spring and provided with a shoulder or flange substantially equal in depth to the thickness of the main leaf, said flange having an extension to engage with the under surface of the main leaf and with an opening in the lower leaf or leaves.

10. In a semielliptic spring, the combination with the main leaf having rounded edges of usual form, of an end plate fitted to the

end of the main leaf and provided with integral side flanges less in depth than one-half the thickness of the main leaf, said flanges being rounded on their inner surfaces to fit the sides of the leaf and having straight outer surfaces to lie flush with the outer edge of the main leaf.

11. In a semielliptic spring, the combination with the main leaf having rounded edges of usual form, of an end plate having an integral extension to engage with the end and under surface of the main leaf, and integral side flanges on the plate less in depth than the thickness of the main leaf, rounded on their inner surfaces to fit the sides of the leaf, and having outer faces lying substantially

flush with the widest portion of the main leaf.

12. The combination with a semielliptic spring composed of a series of leaves, of an end plate supported on the main or top leaf and having an integral extension extending downwardly across the end of the leaf and thence inwardly, engaging permanently with the under surface of the said top leaf. ²⁰

In testimony whereof I affix my signature in presence of two witnesses.
